POTHEAD

Fred C. Meyer, Paterson, and George E. Moffitt,
East Paterson, N. J., assignors to The Okonite-
Callender Cable Company, Incorporated, Pat-
erson, N. J., a corporation of New Jersey

Application December 16, 1932, Serial No. 647,520

1 Claim. (Cl. 247—6)

This invention relates to potheads for electric cables, and is particularly well adapted for use as a pothead construction for cables of the oil filled pressure type such for example as constituting the subject matter of Charles E. Bennett application Serial No. 553,714, filed July 29, 1931.

In such cable systems the insulated conductors of the cable are enclosed in a sheath or a pipe 10 filled with oil under high pressure.

In the drawings accompanying this application two embodiments of the invention have been shown.

Fig. 1 is a part sectional elevational view of one 15 embodiment of the invention;

Fig. 2 is a section on the line 2—2 of Fig. 1; and

Fig. 3 is a view similar to Fig. 1 of a modified 20 form of the invention.

Referring to the drawings in detail and first of all to Figs. 1 and 2, 1 designates a metal sleeve or casing which is secured at its lower end by a 25 wipe joint 2 to the outer sheath 3 of the cable designated 4. It might be noted at this point that the type of enclosure for the cable 4 does not constitute a part of the present invention. The type of enclosure shown comprises an inner lead sheath 5, outer sheath 3 and an intermediate sheath 6 of fabric such as canvas, for example, and as above noted this sheath is filled 30 with oil under pressure, the introduction of this oil causing the inner lead sheath 5 to expand to the extent permitted by the intermediate sheath 6 so as to provide a reservoir for the oil about 35 the exterior of the cable conductors. A steel or iron pipe such as shown in the Bennett copending application above referred to may be used with this pothead construction if desired.

The upper end of the casing or sleeve 1 is provided 40 with a metal plate or cover 7 which is sealed to the end of the sleeve or casing 1 by bolts 8 and gasket 9.

The plate 7 is provided with thimbles 10 screwed thereto and each of these thimbles is 45 equipped with a pressure tube 11, these tubes at their lower end being screwed into the thimbles 10, while their upper ends are provided with a cap 12.

Each of the conductors of the cable is wound 50 with metal tape 13 which is terminated at 14 for example, and to this tape is soldered metal braid 15 wound about the paper insulation of the cable. This braid or tinfoil 15 terminates at 16, for example. Slipped over each cable conductor is a 55 metal cone 17 which, as will be seen from the

drawings, overlaps and contacts with the braid or tinfoil 15 at its lower end.

The conical member 17 at its upper end is spaced slightly from the paper insulation of the paper conductor, and between this conical member 17 and the insulation of the cable conductor is paper or varnished cambric 18 which is wound immediately about the paper insulation of the conductor and terminates at about the point designated 19.

Inasmuch as the pressure tube 11 is considerably larger in diameter than the outside diameter of the conductor of the cable a barrier tube 20 is provided immediately about the insulated conductor between it and the pressure tube 11. The 15 lower end of each barrier tube terminates at about the upper end of the conical member 17, and about the lower end of each barrier tube is applied varnished cambric shown at 21 which is wound about the barrier tube in a conical form, 20 a metal braid 22 being finally applied about this varnished cambric and contacting with the upper end of the cone 17.

As above noted the upper end of each of the pressure tubes 11 is equipped with a cap 12 and 25 the upper end of each conductor 23 of the cable is provided with a connector 24 which is soldered to the conductor or sweated thereto and projects through the end wall of the cap 12 where it is equipped with a nut 25 by which the connector 30 is drawn into oil-tight contact with the cap 12.

As above pointed out the end of the cable sheath or pipe is in communication with the interior of the casing or sleeve 1 and as the pressure tube 11 is in communication with the interior of the 35 casing or sleeve 1 the entire structure will be filled with oil under pressure, the degree of pressure of course depending upon the pressure carried within the cable pipe or sheath.

In Fig. 3 1' designates a casing or sleeve similar to the casing or sleeve 1 of Fig. 1 which is attached to the cable pipe or sheath by a wipe joint 2' and the upper end of this sleeve or casing 1' is capped by plate 7' bolted to the casing. As in the case of Fig. 1 the plate 7' is provided 45 with thimbles 10' screwed thereto, each thimble being equipped with pressure tube 11' screwed into the thimbles. Each pressure tube is provided at its upper end with a ring 26 to which is bolted a cap plate 27. Each conductor of the 50 cable is provided with metal tape 13' wound about the insulation of the cable, this metal tape terminating at 14' above the plate 7'. Above this tape 13', directly about the paper insulation of the conductor, varnished cambric or paper tape 18' 55

is applied, this varnished cambric or paper tape terminating say at 19'. About the lower end of this winding of varnished cambric or paper is applied a winding of copper tape 28 for shielding purposes, the lower end of this shield being soldered to the metal tape 13' of the conductor. About the exterior of the insulated conductor of the cable adjacent the upper end of the pressure tube 11' and between the pressure tube and the 10 conductor insulation are barrier tubes 20'.

Adjacent the lower end of the pressure tube 11' is a shielding cone 29, a similar cone being provided adjacent the upper end of the pressure tube and designated 30.

15 As in the case of the structure shown in Figs. 1 and 2 the pressure tubes 11' are under internal pressure depending upon the pressure carried within the sheath or pipe of the cable.

What is claimed is:—

20 A pothead construction for electric cables of the solid stranded conductor pressure type com-

prising in combination a casing, the lower end of which is secured to the enclosing pipe or sheath of the cable, said casing communicating with the interior of said cable sheath or pipe, a sealed cap for said casing, a pressure tube of insulating material secured to said cap, an insulated cable conductor received by said tube, said tube being sealed at the top and communicating with the interior of said casing, a barrier tube within said pressure tube surrounding the insulated cable conductor, metal tape about the insulation of the conductor adjacent the lower part of said casing, a shielding cone about said tape, insulation about the lower end of said barrier tube terminating adjacent the upper end of said shielding cone, 15 and a metal shield about said insulation, the lower end of said shield being in contact with said cone.

FRED C. MEYER.
